CLAIM

The ornamental design for a bait bucket, as shown and described.

DESCRIPTION

FIG. 1 is a front, top and right-side perspective view of the bait bucket showing my new design;

FIG. 2 is a rear, bottom and left-side perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an alternate configuration in another perspective view thereof; and,

FIG. 10 is a perspective view of a bait bucket in a folded configuration.

The broken lines throughout the drawing figures depict portions of the bait bucket that form no part of the claimed design.
